UNITED STATES PATENT OFFICE.

FRANCIS J. GOODYER AND AMBROSE E. GOODYER, OF MONTREAL, QUEBEC, CANADA.

VENDING MACHINE.

Application filed April 21, 1923. Serial No. 633,658.

This invention relates to new and useful improvements in vending machines and particularly to machines adapted for the sale of music rolls or such like articles, and the 5 object of the invention is to provide a coin controlled mechanism for dispensing said articles from the machine.

Another object is to provide a mechanism into which the coin cannot be inserted when 10 the machine is exhausted of the articles to be vended.

A further object is to provide a device into which the coin cannot be inserted until the operating handle is in a position for without 15 drawing the article to be vended.

A still further object is to provide a coin controlled vending machine which will be simple in operation and inexpensive to manufacture.

20 In our invention we provide a case at the top and bottom of which is mounted a pair of drums, with a pair of endless belts passing around said drums, one set of which is driven to move the belt. Clips are provided 25 on the belt for holding the articles to be vended. A handle is provided for operating the said device, said handle having an extension in which a slot is cut adapted for the reception of a coin. The 30 coin connects the handle with a slot in a guided sliding bar, at one end of which is fitted withdrawing forks having rearwardly projecting tails to hold the articles against premature rise. The forks engage 35 with the article and deliver it to a delivery chute on the front of the machine. The slot in the guided bar is adapted to coincide with a slot in the guides so that when the article is ready for delivery the coin drops through 40 this slot and falls into a coin receptacle. A coin slot closing mechanism is provided to close the slot when the machine has become exhausted of the articles to be vended, said mechanism being operated by the rolls in 45 the clips.

In the drawings:

Figure 1 is a perspective view of the device.

Figure 2 is a cross sectional elevation of 50 the machine showing the mechanism.

Figure 3 is a plan view of the coin controlled mechanism.

Figure 4 is an elevation looking on the back of the machine showing the belts.

55 Figure 5 is a perspective view of the coin controlling mechanism.

Figure 6 is a detail perspective view. Referring more particularly to the drawings, 11 designates a case which is provided with a hinged hollow extension 12 in the front part and having a slot 13 cut in it for delivering the vended articles through the medium of an inclined chute 14 placed within the extension. Mounted on the drums 15 which are mounted on the spindles 16 situated one at the top and one at the bottom are the endless belts 17 spaced from one another and provided with spring clips 18 adapted to hold the rolls 19 which are the articles to be vended. A spring 20 is mounted on the upper spindle and adapted to give a motion to the belt as shown in Figure 2 by the arrow "A". Guides 21 are provided to hold the belts in position. A locking device is provided to hold the belt against movement when the case is open for refilling the empty spring clips. This locking comprises a pin 22 placed through the upper spindle and adapted to revolve with the same. Slidably mounted within the guides 23 attached to the side of the case is an engaging bar 26 provided with a handle 25. The bar 26 engages with the pin 22 when locking the movement of the belt and can be pulled out of engagement with the pin 22 when the machine is in the operative position. Passing through the extension 12 is a bar 24 which is provided with a handle 27. This bar is of the double or forked type and is provided with a slot and is made wide and thick enough to receive a coin equal in commercial value to the value of the articles to be vended. Upon the bar 24 is mounted a withdrawing fork support 28 which is also provided at one end with fingers 29 adapted to coincide with the fingers in the bar 24. This support is also provided with a slot 29^a cut in the fingers adapted to receive the aforementioned coin, said coin engaging with the bar 24 and the fingers 29, so that when the handle is pulled both the bar 24 and the withdrawing fork support will move in unison. At the end of the support 28, remote from the handle, is mounted the withdrawing fork 30 which is provided with a tail piece 31 adapted to prevent premature rise of the belts, said tail piece being so positioned to engage with the next article, or roll, when one of the rolls has been withdrawn, a recess 32 being formed in the withdrawing fork to pull the roll from the belt and deliver it to the chute 110

14. The fingers of the withdrawing fork support and the bar 24 are mounted between upper guides 23 and a lower guide 34, said lower guide extending across the total width 5 of the bar 24. An aperture 35 is cut in the lower guide and so positioned that as soon as the roll is delivered to the chute the coin will pass through said aperture into a coin receptacle 36 situated within the extension 10 12 of the case 11. A spring 37 is mounted between the fingers and fastened to the inner face of the extension 12 to assist the coin through the aperture into the receptacle 36. The end 38 of the bar 24 is adapted 15 to engage with shoulders formed in the withdrawing fork support when said bar is moved inwardly only. To provide a quick return for the handle a rod 39 is oscillatably mounted on a pin 40 20 passing through the fingers of the forked end of the handle extension, and around said rod is placed a compression spring 41 engaging at its upper end with a collar 42 fixed to the rod and at its lower end with a 25 bracket 43 extending across the coin receptacle 36 and terminating in right angular extensions 43' which are bolted or otherwise secured to the side walls of the coin receptacle. The rod passes through an aperture 30 43' of said bracket and is so positioned that the spring is first compressed when the handle is withdrawn and as soon as the rod passes the vertical position or dead centre, the handle is pushed outwardly by the spring 35 thus ensuring delivery of the roll and reception of the coin. The reverse motion takes place when returning the handle and fork to the operative position. The handle is pushed inwardly until the rod passes the 40 dead centre and the spring returns the fork and handle to the operative position. The coin is delivered to the machine through a coin receiver 44 which comprises a flat tubular device which guides the coin towards 45 the engaging slots in the fingers of the handle extension and the fingers of the withdrawing fork support. To prevent coins from being inserted into the machine when the machine becomes exhausted an oscillatably mounted lever 45 with one end 46 pivotally connected to a bracket 47 is attached to the inner side of the extension 12. The other end 47' is provided with a rounded slot 48 adapted to receive a pin or rounded end 49 50 of a lever 50 which is oscillatably mounted on a pin 51 mounted on the side of the extension 12. This lever is bent at its lower end and so positioned that said lower end engages with the rolls or articles to be 55 vended and is moved by the movement of same, so that the lever 45 has a horizontal motion. A projection 52 is provided on the lever 45 and adapted to enter a slot 53 cut in the coin chute when the machine is empty 60 or when withdrawing a roll from the ma- chine. The operation of the device is as follows: A coin is inserted in the machine through the coin chute and so guided that it connects the handle, fork extension and the withdrawing fork support, the withdrawing fork engaging with a roll which is positioned within the recess formed in the withdrawing fork. The handle is then pulled against the compression spring device thereby pulling one roll clear of the spring 70 clips in the belt and carrying it forward to the delivery chute. The belt is provided with a spring operating device which causes it to move in the direction indicated by the arrow "A" in Figure 2. To prevent premature rise of the belt the extension or tail piece 31 engages with the next roll and holds it in position until the handle is returned to the operative position, i. e., with the roll 75 engaging with the withdrawing fork recess. While the handle is withdrawn the lever 50 drops to engage with the next roll thereby closing the coin slot. When the machine is exhausted of the articles to be vended the lever 50 drops thereby operating the lever bar 45' and closing the coin slot through the medium of the projection 52. To return to the operative position the handle is first pushed against the spring 41 until the rod 39 passes the dead centre, the spring then 80 controls the movement of the handle and the withdrawing forks. The handle when in the withdrawn position allows the coin to engage with a slot cut in the lower guide and a spring presses the coin through the slot into a coin receptacle placed beneath the mechanism. To provide a means for holding the belt from movement when the extension is opened the hand operated lever situated at the top of the case is pressed 85 upwardly so that it engages with a pin passing through the upper spindle on which are fixedly mounted the belt drums. 90

To prevent backward movement of the handle during the cycle of operations, saw toothed slots 54 are cut or formed in the bottom guides. These slots allow free movement of the handle in the withdrawing position but if the handle is pushed inwardly the coin engages with saw tooth slots and locks it against inward movement. Thus the machine must be operated through its full cycle of operations and the coin delivered into the coin receptacle before another roll can be withdrawn or delivered 95 from the machine. 100

To prevent operation of the machine when it is empty, a dummy roll 56 is secured to the belt. No part of this roll extends beyond the outer edges of the belt to engage with the coin slot closing mechanism which is operated by the lever 50. The dummy roll engages with the recess 32 and prevents belt movement. The coin slot is closed and no coin can be inserted into the coin chute. 105

Having thus described our invention, what we claim is:—

1. Ejector operating means for vending machines comprising a pair of superimposed independently slidable members, said members being formed with longitudinal slots and with coin receiving recesses at opposite sides of each slot, the coin receiving recesses in one member being adapted to register with the coin receiving recesses of the other member in the normal position of the members, a stop carried by one member and engageable with the other member to limit independent movement of the members in one direction, a chute arranged to guide a coin into the registering recesses of the members to lock the members together for unitary movement, a coin receptacle underlying the slots in said members, means for engaging and causing the coin to pass into the receptacle upon movement of the members in one direction, a bracket underlying said members, a rod having one end passing through an aperture in said bracket so as to permit the rod to oscillate and also have a reciprocating movement in said aperture and a spring encircling said rod between said bracket and an abutment on the rod and adapted to be compressed when the rod is oscillated.
2. Ejector operating means for vending machines comprising a pair of superimposed independently slidable members, said mem-

bers being formed with longitudinal slots and with coin receiving recesses at opposite sides of each slot, the coin receiving recesses in one member being adapted to register with the coin receiving recesses of the other member in the normal position of the members, a stop carried by one member and engageable with the other member to limit independent movement of the members in one direction, a chute arranged to guide a coin into the registering recesses of the members to lock the members together for unitary movement, a coin receptacle underlying the slots in said members, means for engaging and causing the coin to pass into the receptacle upon movement of the members in one direction, a bracket underlying said members, a rod having one end passing through an aperture in said bracket so as to permit the rod to oscillate and also have a reciprocating movement in said aperture, and the other end of the rod being pivoted to the lowermost member, an abutment on said rod, a spring encircling the rod between the abutment and the bracket and arranged to be compressed by oscillating movement of the rod in either direction.

In witness whereof, we have hereunto set our hands.

FRANCIS J. GOODYER.
AMBROSE E. GOODYER.
